UNITED STATES PATENT OFFICE

CHARLES WESLEY JONES, OF GLEN RIDGE, NEW JERSEY, ASSIGNOR TO SONS-CUNNINGHAM REED & RATTAN CO., INC., OF NEW YORK, N. Y., A CORPORATION OF NEW YORK

DESIGN FOR A FRAME OF A CHAIR OR SETTEE

Application filed April 8, 1930. Serial No. 35,191. Term of patent 7 years.

To all whom it may concern:

Be it known that I, CHARLES WESLEY JONES, a citizen of the United States, residing at Glen Ridge, in the county of Essex and State of New Jersey, have invented a new, original, and ornamental Design for the Frame of a Chair or Settee, of which the following is a specification, reference being had to the accompanying drawing, forming part thereof.

Fig. 1 is a perspective view of a chair frame showing my new design, it being understood that the design, shown in full lines, is repeated at the other end of the chair as indicated by dotted lines;

Fig. 2 is a side view thereof.

I claim:

The ornamental design for a frame of a chair or settee, as shown and described.

In witness whereof, I have hereunto set my hand.

CHARLES WESLEY JONES.
